UNITED STATES PATENT OFFICE.

WILLIAM R. NICOLL, JR., OF OWATONNA, MINNESOTA, ASSIGNOR TO DAVIS-WATKINS DAIRYMEN'S MANUFACTURING COMPANY, OF NORTH CHICAGO, ILLINOIS, A CORPORATION OF DELAWARE.

RIPENER AND PASTEURIZER.

1,285,330.

Specification of Letters Patent. Patented Nov. 19, 1918.

Application filed June 8, 1917. Serial No. 173,508.

To all whom it may concern:

Be it known that I, WILLIAM R. NICOLL, Jr., a citizen of the United States, residing at Owatonna, in the county of Steele and 5 State of Minnesota, have invented certain new and useful Improvements in Ripeners and Pasteurizers, of which the following is a specification.

This invention relates to a device for controlling the temperature of liquid in a vat, such for example as milk or cream in a 10 creamery, and the principal object of the invention is to provide a new and improved construction, combination and arrangement 15 of parts for effectively and efficiently accomplishing the desired result.

In the accompanying drawings, Figure 1 is a side elevation of a device constructed in accordance with the principles of my invention; Fig. 1^a is a fragmentary view showing one of the doors open and one closed; Fig. 2 is a view of the driving end; Fig. 3 is a sectional detail of the driving end construction taken on the line 3—3 of Fig. 2, 25 and Fig. 4 is a sectional view of an injector.

In order to produce a uniform grade of butter which does not vary in quality from day to day, it is found necessary to have absolute control of the ripening of cream 30 by first heating it to a pasteurizing temperature uniformly throughout and then allowing the cream to cool and ripen in the regular way. The present invention is for the purpose of accurately controlling and regulating the temperature of cream in the making of butter, although, of course, it may have a more general application to the heating and cooling of any liquid.

In the present invention, a vat 1 is mounted 40 on spaced supports 2 each in the form of a saddle with two legs to which the vat is secured with perforated brackets 3 extending from the sides of each support to carry a circulating pipe 4 on one side and 45 a stub pipe 5 on the other, the pipes acting as spacers for holding the supports in place.

At the top of the vat are two doors 6 hinged about the longitudinal center and supported by brackets 7 at the ends which 50 extend a substantial distance above the doors with connecting arms secured to the doors so that when either one is raised, as shown in Fig. 1^a, there is a considerable distance

between the door and the top of the ripening coil 9 within the vat. This is for the purpose of making the coil easy of access for cleaning. At the ends of the vat are pivoted arms 10 with notches 11 at the ends which are adapted to engage projecting pins 12 extending from the doors 6, so that the doors 60 may be held in a number of open positions. At the edges of the vat are a number of clamps 13 for engaging the edges of the doors and holding them in position.

The walls of the vat are made up with a 65 body 14 of wood which is covered on the outside with sheet metal 15. On the inside of the body 14 is a layer 16 of insulating material, preferably of two thicknesses, and covering the insulating material is a sheet 70 17 of water-proof paper. On the inside is a metal lining 18 preferably of copper which is tinned or coated on the inside and preferably at the seams making a sanitary and easily cleaned construction. The water- 75 proof paper 17 is interposed between the metal lining and the insulation 16 to prevent any moisture getting to the insulation that might result from the changing of temperatures, causing the lining to sweat.

Attached to each end of the vat is a plate 19 having a packing box 20 of sufficient length to extend through the wall of the vat, and threaded at the inner end for the reception of a collar 21 which is screwed tightly 85 against the inside metal lining 18 of the vat thereby making a fluid tight and sanitary joint. The ripening coil 9, within the vat, is made in the form of a spiral to each end of which is attached a T 22 with a partition 23 cast in one of the opposite openings instead of using a wooden plug, as has previously been the practice in constructions of this kind. Connecting the T's 22 at the ends of the coil is a pipe 24 which is therefore closed at the ends by the partitions 23 so that no fluid is allowed to flow directly between the T's. This pipe 24 spaces the T's apart and the entire coil 9 may therefore be placed in or removed from the vat 90 when the end supports are disengaged.

In order to support the coil 9 within the vat, a pipe 25, threaded at the inner end, is inserted through the packing box 20 and threaded into the end of the T 22. A packing gland 26 and packing 27 make a tight 105

joint around the pipe 25 and prevent leakage from the vat. The outer end of each pipe 25 is inserted into a bearing 28 forming a part of a supporting bracket 29 which is secured to plate 19. A fluid tight joint is also made in this bearing by means of packing 30 and a gland 31.

At the driving end a gear 32 is secured to the pipe 25 between bracket 29 and the plate

- 10 19, and meshing with this gear is a driving pinion 33 mounted on a shaft 34 which carries pulleys 35, one being loose and the other fast on the shaft. Extending upwardly from the bearing 28 is a pipe 36 with 15 a faucet 37 at the upper end, and connected to the outer end of the bearing is a pipe 38 which is connected through a check valve 39 and short pipes 40 with the circulating pipe 4 at the side of the vat. The pipe 36 20 admits air to the coil for controlling the amount of circulating fluid passing in the coil, when the coil is rotated and acting as a pump or self-circulating means.

At the other end of the vat is a tank 41 into which the end of the pipe 4 extends with an injector connected thereto comprising a fitting 42 (see Fig. 4) having an opening opposite the pipe 4 for the insertion of a steam pipe nozzle 43 and with lateral openings 44 surrounding the nozzle 43 for the admission of liquid from within the tank 41. The nozzle 43 is connected, by means of a pipe 45, to a suitable source of steam pressure or cold water supply, neither of 35 which are shown or described. Connected to the bearing 28 at this end of the vat is a pipe connection 46 which discharges into the top of tank 41 thereby permitting the liquid in the tank to be reused. Extending 40 from the top of the tank is an overflow pipe 47.

The construction shown is sanitary not only because the interior of the vat and all of the parts are easily accessible for cleaning, but also because there is very little chance for leakage and in fact a minimum number of packing joints are needed, so that there is less opportunity for leakage. The entire coil 9 is easily removable from within 50 the vat by simply loosening the brackets 29 and unscrewing the pipes 25, which constitute both the bearings and the supports for the coil, from their engagement with the T's 22.

55 In operation, the liquid to be tempered is placed in the vat and if the temperature is to be raised or lowered, a heating or cooling liquid is forced through the spiral coil 9, the coil being rotated at the same time by 60 means of the driving pulley so that the liquid in the vat will be uniformly tempered, not only by the movement of the liquid itself, but by the circulation of the tempering fluid in the coil. The rotation of the 65 coil 9 either with or without the fluid under

pressure causes it to act as a pump or a self-circulating means; when pressure is applied to the pipe 4 for forcing liquid through the coil 9, the valve or faucet 37 is closed, but when the coil is self-circulating by its rotation, the flow of circulating liquid is controlled by increasing or decreasing the air admitted through the faucet.

I claim:

1. In a ripener and pasteurizer a vat 75 open at the top, a circulating coil rotatable therein about a longitudinal axis closely adjacent the top of the vat, doors for the top of the vat rotatable about a longitudinal center, and means comprising brackets for 80 hinging the doors at a point above the vat so that when the doors are open there will be an additional clear space between the coil and the adjacent edge of the doors.

2. In a ripener and pasteurizer, the combination with a vat, of a coil rotatable therein, a T member for each end of the coil, means for holding the T's at a spaced distance apart, a tubular member extending through each end of the vat and threaded 90 into the T for forming connection with the coil, a plate secured to the end of the vat having a packing box through which the tubular member extends, packing and a packing gland for making a fluid-tight connection with the said box, and a bearing for the outer end of each tubular member, a bracket securable to the end of the vat having a bearing portion at a distance from the end of the vat into which the end of the 100 tubular member extends, and packing means surrounding the outer end of the tubular member and in conjunction with the bearing portion of the bracket for making a fluid-tight connection therewith.

3. In a ripener and pasteurizer, the combination with a vat, of a coil rotatable therein, a T member for each end of the coil, means for holding the T's at a spaced distance apart, and a tubular member extending through each end of the vat and threaded 110 into the T for forming connection with the coil.

4. In a ripener and pasteurizer, the combination with a vat, of a coil rotatable therein, a T member for each end of the coil, means for holding the T's at a spaced distance apart, a tubular member extending through each end of the vat and threaded 115 into the T for forming connection with the coil; a plate secured to the end of the vat having a packing box through which each tubular member extends, and means including a packing gland for making a fluid-tight connection with said box around the 120 tubular member.

5. In a ripener and pasteurizer, the combination with a vat, of a coil rotatable therein, a T member for each end of the coil, means for holding the T's at a spaced dis-

tance apart, a tubular member extending through each end of the vat and threaded into the T for forming connection with the coil, means at the end of the vat forming a fluid-tight connection through which the tubular member extends; and a bearing for the outer end of each tubular member comprising a bracket attached at the end of the vat and having a bearing portion and

packing means at the outer end of the ¹⁰ tubular member.

In testimony whereof I have signed my name to this specification, on this 31st day of May, A. D. 1917.
